UNITED STATES PATENT OFFICE.

ABRAHAM REED, OF CHICAGO, ILLINOIS, ASSIGNOR OF ONE-HALF HIS
RIGHT TO WILLIAM T. COOLEY, OF SAME PLACE.

IMPROVEMENT IN EXTENSION TABLES.

Specification forming part of Letters Patent No. 137,148, dated March 25, 1873.

To all whom it may concern:

Be it known that I, ABRAHAM REED, of the city of Chicago, in the county of Cook and State of Illinois, have invented a certain new and useful Improvement in Extension Tables, of which the following is a full description, reference being had to the accompanying drawing making a part of this specification, in which—

Figure 1 is a plan view with the leaves and cover removed; Fig. 2, an under-side view of the frame and rollers; Fig. 3, a view of a single hinged leaf; and Fig. 4, a view of the bracket.

The object of my invention is to provide an extension-table with a pocket having its bottom formed of rollers, in which the removable leaves may be placed.

In the drawing, A A¹ A² represent longitudinal bars; C, legs of the table; B B', end pieces; and E, side pieces, all of which parts are constructed in the usual manner. To the under side of the longitudinal bars A A¹ A² I connect rollers a a' b c, by means of suitable bearings d. e f are cross-bars, the former attached to the under side of A¹, the latter to the end piece B. The bars A A with the rollers a a' form a pocket to receive the leaves, the leaves resting upon the rollers a a' when the table is open. When the table is closed,

the rollers are brought into the position shown in Fig. 2. As a' passes along under the leaves, b and c take its place and pass under the leaves. The four rollers are so arranged that when the table is closed the leaves rest upon the four rollers. In order to bring the leaves within the space formed by the bars A A and rollers, it is necessary to make them in two parts, D D', hinged together by suitable hinges g, as shown in Fig. 3, so that each leaf before being placed in the pocket must be folded together, occupying but half the space in length that it does when open. In each leaf I use four dowels, i, which aid in supporting them when in use. The bar f serves the purpose of a guard, to prevent the first leaf from dropping down while being placed in the pocket. I support each end leaf by a bracket, F, having two pins, k k, by means of which it can be hinged in suitable bearings. This bracket F is represented in Fig. 4.

What I claim as new is as follows:

The combination of the bars A A¹ A² and depressed rollers a a' b c in an extension table, substantially as and for the purposes specified.

A. REED.
